DESIGN FOR A ROUGE HOLDER

Louis H. Pfohl, Forest Hills, N. Y., assignor to Design Center Inc., New York, N. Y., a corporation of New York

Application September 12, 1945, Serial No. 122,037

Term of patent 3½ years

(Cl. D86—10)

To all whom it may concern:

Be it known that I, Louis H. Pfohl, a citizen of the United States, residing at Forest Hills, L. I., in the county of Queens, city, and State of New York, have invented a new, original, and ornamental Design for a Rouge Holder, of which the following is a specification, reference being had to the accompanying drawing, forming part thereof.

In the drawing:

Fig. 1 is a top plan view of a rouge holder in closed position showing my new design;

Fig. 2 is a top plan view in open position;
Fig. 3 is a plan view of the reverse side of the top of the holder shown in Fig. 1;

Fig. 4 is a side elevation of the holder in closed position.

I claim:

The ornamental design for a rouge holder, substantially as shown.

LOUIS H. PFOHL.
